UNITED STATES PATENT OFFICE.

PETER SCHECKLER, OF ORANGEVILLE, AND CHARLTON M. GREGORY, OF WARREN, ILLINOIS.

IMPROVEMENT IN MAGAZINE FIRE-ARMS.

Specification forming part of Letters Patent No. 158,001, dated December 22, 1874; application filed November 18, 1874.

To all whom it may concern:

Be it known that we, PETER SCHECKLER, of Orangeville, in the county of Stephenson, and CHARLTON M. GREGORY, of Warren, in the county of Jo Daviess, and State of Illinois, have invented certain new and useful Improvements in Breech-Loading Fire-Arms; and we do hereby declare the following to be a full, clear, and exact description of the invention, such as will enable others skilled in the art to which it pertains to make and use it, reference being had to the accompanying drawings, which form part of this specification.

Our invention relates to an improvement in breech-loading fire-arms; and consists of the combination of devices which will be more fully described hereafter.

The accompanying drawings represent our invention.

Figure 1 is a side elevation of a gun embodying our invention, with part of the stock removed. Fig. 2 is a plan view of the cartridge-carrier. Fig. 3 is an enlarged sectional view through the breech and stock. Fig. 4 is an inverted view of the plate that covers the cartridge-carrier. Figs. 5, 6, 7, 8, 9, 10, 11, and 12 are detail views of the same.

A represents the stock, and B the barrel, of the gun. The cartridge-carrier *a* is moved by the lever *L* attached to its under side, which carrier, when the lever *L* is in its proper position, closes the rear end of the barrel *B* by a block or breech, *c*, attached at its forward end, from which block protrudes the cartridge-extractor *e*, which enters into corresponding notches under the back end of the barrel. The carrier *a* is long enough to receive three cartridges on its top, is flat upon its front end next to the barrel, while the rest of its surface is concave and inclines backward toward the magazine. Where the incline begins is placed a spring-stop, *d*, to prevent the cartridges from sliding back, and another spring-stop, *f*, with a U-shaped end, occupies the lower part of the carrier, which part terminates in a hook, *g*, reaching backward beyond the carrier, which hook lifts the cartridge from the chain *C* and draws it forward. Opposite the U-shaped spring-stop *f*, at one side of the carrier, is pivoted a slide, *h*, which extends backward and

has on the inside of its end a projection, which, when the carrier is moved backward, partly turns a horizontal ratchet pivoted to the plate *b*, whereby an endless chain, *C*, carrying cartridges, is moved. This slide *h* has another projection near its pivot, which causes the bent lever *m* pivoted above it to turn down the cartridges before they are drawn forward by the hook *g* toward the barrel. The spring *n* on the opposite side to the slide *h* serves to hold and guide the cartridges in place, and the springs *i* and *l*, secured to the under side of the plate over the carrier, perform a similar service. Pivoted near the upper edges of the side plates at *t* are the arms of a cartridge-guide, *r*, one of which arms has a projection, *l*, under its pivot, which moves in a groove at the side of the carrier, and is there met by a shoulder, *2*, by which the front end of the guide is bent downward to the breech. An endless chain, *C*, formed of cylindrical longitudinal sections, revolves around the two pinions *3* pivoted upon the plate *b*, and each time the lever *L* is operated the chain is moved partly around by means of the slide *h*, which catches against one of the arms of the ratchet-wheel *y*. Under the plate *b* is a knob, *p*, by which the pinion *3*, around which the chain moves, can be turned, so that cartridges may be put in their places in the chain through an opening in the side of the stock of the gun. The lever *I*, when bent downward, operates upon the tumbler *t*, by turning it, for the sear to hold in a cocked position, from which it may be released by the trigger. Hence, by bending down and holding the lever *I* with one hand and pulling the trigger with the other, and then allowing the lever gently to reassume its former position, the gun will be uncocked.

The cartridges having been placed vertically upon the chain by drawing the lever *L* forward to its full extent, the hook *g* will be inserted under the cartridge, the cartridge laid down by the bent lever *m*, and the gun cocked. By moving the lever *L* back to its place the cartridge is drawn forward and prevented by the spring *f* from moving backward, and the bent lever *m* restored to its former position by the returning slide *h*. The first cartridge removed from the chain is now just its own length moved toward the breech of the gun. By repeating

the motions of the lever a second time another cartridge will be presented in the place of the former, the wheel upon which the chain rests having turned just enough to move the width of one cartridge. This cartridge will then be turned down and drawn forward, pushing the cartridge, already upon the carrier, its own length forward. Thus the first one has passed over two spaces, and the second one is in the place just vacated. Continuing the same operation four times will place the first cartridge in the barrel, and then there will be upon the carrier three more. In this manner as many shots, without reloading the gun, may be fired as the capacity of the magazine admits, for holding cartridges. The cartridge-extractor, at the time when the lever is pushed forward, draws the shell from the barrel and drops it out through the opening under the breech.

On the plate *b*, at its end, is a device, *j*, for regulating the tension of the chain, which consists of a sliding plate upon which one of the pinions is pivoted, held in place by a pin moving in a slot and secured by a screw.

Having thus described our invention, we claim—

1. In a magazine-gun, the endless chain *C*,

adapted to be operated through the medium of the knob *p*, for the purpose of charging the magazine through an opening in the side of the stock, substantially as described.

2. The combination of the cartridge-carrier, having the hook *g* upon its end, the slide *h* for operating the endless chain, and the spring-stops *d f* for preventing the backward motion of the cartridges, the parts being arranged to operate substantially in the manner and for the purposes specified.

3. The combination, with the carrier, of slide *h* for moving the chain, and bent lever *m* for laying down the cartridges, substantially as described.

4. The combination of the sliding breech and pivoted guide *r*, for presenting the cartridge to the breech, substantially as specified.

In testimony that we claim the foregoing we have hereunto set our hands this 7th day November, 1874.

PETER SCHECKLER,
CHARLTON M. GREGORY.
